CLAIM

The ornamental design for a utility tray, as shown and described.

DESCRIPTION

FIG. 1 is a left isometric view of the utility tray showing our new design;

FIG. 2 is a right isometric view thereof;

FIG. 3 is a top view thereof;

FIG. 4 is a left side view thereof;

FIG. 5 is a bottom view thereof; and,

FIG. 6 is a grouped view thereof.

The broken line showing of stacked trays and a tray holder is included for the purpose of showing the environment of the utility tray and forms no part of the claimed design.
